UNITED STATES PATENT OFFICE.

LEVI K. FULLER, OF BRATTLEBOROUGH, VERMONT, ASSIGNOR TO THE
ESTEY ORGAN COMPANY, OF SAME PLACE.

REED-ORGAN.

SPECIFICATION forming part of Letters Patent No. 430,382, dated June 17, 1890.

Application filed January 8, 1889. Serial No. 295,754. (No model.)

To all whom it may concern:

Be it known that I, LEVI K. FULLER, a citizen of the United States, and a resident of Brattleborough, in the county of Windham 5 and State of Vermont, have invented certain new and useful Improvements in Reed-Organ, of which the following is a specification.

My invention relates to the construction of the cases of reed-organs; and the object of 10 the invention is to facilitate access to the interior of the case for repairs, adjustment, &c.

My invention will be fully described hereinafter, and its novel features carefully defined in the claims.

15 In the drawings which serve to illustrate my invention, Figure 1 is a front elevation of the upper portion of an organ embodying my improvements. Fig. 2 is a sectional plan of the same. Fig. 3 is a vertical transverse section 20 of the upper portion of the organ on a larger scale than Figs. 1 and 2. Figs. 4 and 5 are views, on a scale somewhat smaller than Figs. 1 and 2, illustrating the application of my improvements to an organ-case. Fig. 4 25 is a front view of the organ, and Fig. 5 is a section on line 5 5 in Fig. 4. Fig. 5^a is a detached fragmentary view on a larger scale.

The improvements relate to the construction of the music-desk, key-slip, and front 30 board, whereby these parts are provided with non-positive retainers or fastenings, such as will render them readily detachable from the fixed portions of the organ-case without manipulation of the fastenings.

35 *a a* are the ends of the case, which may have the usual form. Between these ends, where they rise above the key-board, is situated the inclined music-desk *b*. This desk is constructed so as to be readily removable without 40 out the necessity of drawing bolts, screws, or the like.

On the back of the desk *b* are secured, one at each end, hook-buttons *c*, which engage, respectively, pins or studs *d* in the ends *a a* of the case. These pins form supports for the 45 desk and also pivot-points on which it turns when the desk is being removed.

At its upper front corners the desk rests against suitable stops *e* on the ends of the 50 case, and it is held up to these stops by spring-detents *g*, the ends of which bear on inclines

h', formed on the rear face of the desk at its ends. Thus the desk is held firmly in its position; but it may be readily removed by pressing its upper part (above the pins *d*) 55 forcibly back, when the inclines *h* on the desk act to press in the spring-detents and allow the desk to be pushed past them. The hook-buttons *c* may now be lifted off from the pivot-pins *d*, and the desk drawn out at the front 60 of the organ. The desk may be replaced by reversing these operations, the engagement of the buttons with the pivot-pins being first effected, and the lower part of the desk then pressed forcibly back until the detents spring 65 out and take behind it. The free ends of these spring-detents may be slightly rounded, so as to permit of their ready disengagement in the manner described.

i is the key-slip, which is arranged in the 70 front of the case and just below the keys. Ordinarily this key-slip is secured to the key-blocks *j* or to the ends *a* of the case with bolts or screws.

In order to render the key-slip readily removable without the necessity of drawing bolts, screws, or the like, or indeed the manipulation of any fastenings, I arrange the lower edge of the key-slip *i* to engage a retaining-groove in the upper edge of the fixed rail 75 *k*, and on the back of the key-slip I mount suitable buttons or catches *l*, one at each end, which engage, respectively, spring-latches *m*, mounted on some fixed part of the case. These latches hold the key-slip quite firmly 85 in place; but it may be removed by forcibly pulling its top outward or forward, pressing downward on it at the same time. It may be replaced by setting its lower edge in the groove in the rail *k* and then pushing its top inward 90 until the latches *m* are heard to engage the catches *l*.

It is desirable to remove the front board of the organ at times in order to afford access to the interior, and I provide means for securing said front board non-positively to the fixed parts of the organ-case, said securing device being similar to that employed for the key-slip. This construction is illustrated in Figs. 4, 5, and 5^a, to which reference may be 100 had for a better understanding of the following description. *n* is the front board, the

lower edge of which engages a groove or recess in a fixed rail *o*. The upper edge of the front board rests in a rabbet in an upper rail *p*. On the inner faces of the ends *a* of the organ are secured spring-detents *s*, one at each end of the organ, and when the front board is in place these detents take behind inclines or bevels on the ends of the front board at these points, as seen in Fig. 5^a, and hold the board firmly up to the stop formed by the rabbet in rail *p*. The board may be removed by forcibly drawing its top outward or forward until it is free from the detents, the latter yielding to allow it to pass. In replacing the board the lower edge thereof is made to engage the groove in the bottom rail *o*, and the upper part of said board is then pushed in or back until the spring-detents *s* take behind it. As the detents are arranged close up under the projecting part of the organ, they will not be visible to the ordinary observer.

The front board may be provided with knobs or handles *u* or some similar device to enable one to grasp it for removal.

I prefer to provide two retaining or securing devices for the music-desk, the key-slip, and the front board, one device being placed at each end of the removable part; but good results may be attained with but one fastening for the part. The retaining devices are concealed, as herein shown, and I prefer that they should be so concealed, so that they may not mar in any degree the appearance of the organ. These devices are all non-positive, in the sense that they may be disengaged by pressure alone exerted on the part, and this is their notable characteristic. Nevertheless the fastenings are of such a nature that they cannot be affected by ordinary shrinking of the wood of the parts.

Having thus described my invention, I claim—

1. An organ-case having a removable music-desk and a spring which retains the desk in place in a non-positive manner, as described, the said case and desk having also reciprocal means of engagement, substantially as set forth. 45

2. An organ-case having a removable key-slip and a spring which retains the said slip in place in a non-positive manner, as described, the said case and slip having also reciprocal means of engagement, substantially as set forth. 50

3. An organ-case having a removable front board *n* and a spring which retains said board in place in a non-positive manner, as described, the said case and board having also reciprocal means of engagement, substantially as set forth. 55

4. The combination, with the ends of an organ-case provided with pivot-pins *d*, spring-detents *g*, and stops *e*, of the music-desk provided at its back with hook-buttons engaging the pins *d*, and with inclines *h* at the points where the spring-detents bear thereon. 60

5. The combination, with the fixed portion of the organ-case provided with a spring-latch *m* and the rail *k*, of the key-slip *i*, engaging a recess in said rail at its lower edge and provided on its inner face with a catch *l*, 70 engaging the said spring-latch.

6. The combination, with the fixed portion of an organ-case provided with a spring-detent *s* and a recessed rail *o*, of the front board *n*, its lower edge engaging the recess in said rail and provided with a bevel at the point where it is engaged by said detent. 75

In witness whereof I have hereunto signed my name in the presence of two subscribing witnesses.

LEVI K. FULLER.
